P. J. DWYER.
SAFETY RAZOR STROPPING DEVICE.
APPLICATION FILED SEPT. 4, 1919. RENEWED APR. 13, 1922.
1,425,081.

Patented Aug. 8, 1922.

UNITED STATES PATENT OFFICE.

PATRICK J. DWYER, OF NEW YORK, N. Y.

SAFETY-RAZOR-STROPPING DEVICE.

1,425,081.

Specification of Letters Patent. Patented Aug. 8, 1922.

Application filed September 4, 1919, Serial No. 321,644. Renewed April 13, 1922. Serial No. 552,229.

To all whom it may concern:

Be it known that I, PATRICK J. DWYER, a citizen of the United States, residing at New York city, in the county of New York and State of New York, have invented certain new and useful Improvements in Safety-Razor-Stropping Devices, of which the following is a specification.

This invention has relation to stropping devices for safety razor blades, and has for an object to provide a strop particularly designed to receive a blade of the type having cutting edges at both sides, means being provided to protect one edge while the other is being stropped, to thereby prevent injury to the strop and to permit more convenient manipulation of the device as an entirety.

Another object of the invention is to provide a device of the character set forth including a shield or guard pivotally mounted to engage either edge of the blade with means for automatically securing the guard in place subsequent to its proper adjustment.

In addition to the foregoing, this invention comprehends improvements in the details of construction and arrangement of parts, to be hereinafter described and particularly set forth in the appended claims.

In the accompanying drawings in which similar and corresponding parts are designated by the same characters of reference throughout the several views in which they appear.

Figure 1 is a view in elevation of a safety razor blade holder of conventional type illustrating the embodiment therein of my improvement.

Figures 2 and 3 are transverse and longitudinal sections respectively taken on the line 2—2 and 3—3 of Figure 1.

Figure 4 is a detail section taken on the line 4—4 of Figure 1.

Figure 5 is a fragmentary view in plan of a modified form of my invention and

Figure 6 is another modified form of my invention illustrating separable parts thereof.

With reference to Figures 1 to 4 of the drawings, 10 indicates a plate forming a part of a conventional form of stropping device, the latter having an extension 11 which may be pivotally held within a casing or the like. The blade 10 is provided with a pair of slots 12 to receive the pins 13

which project from the plate 14 forming a part of my invention. Interposed between the plates 10 and 14 is the safety razor blade 15 having cutting edges at opposite sides and openings through which the studs 13 project. After the parts are assembled in the manner stated the plate 10 is moved relatively to the plate 14 whereupon the studs 13 automatically interlock within the slots 12 thereby securing the plates 10 and 14 against separation. Oppositely extending trunnions 16 are formed upon the ends of the plate 14, said trunnion seating in parallel end portions 17 of a guard member, 70 the guard portion 18 of which connects the member 17. The adjacent faces or edges of the portion 17 are formed with V-shaped grooves 19 and the ends of the plate 14 are bevelled to seat in said groove when the guard member is in one adjusted position or the other as the case may be to secure the guard member against movement.

In operation, the parts are assembled in the manner stated and the blade is stropped in the usual manner. It will be observed that the guard 18 lies in contact with one cutting edge of the blade, thereby protecting the same and preventing the edge from becoming injured or the strop from becoming mutilated. After one edge has been stropped it is but necessary to rotate the guard 18 whereupon the portion 17 thereof will spread apart slightly to release themselves from the bevelled end of the plate 14 whereupon the guard may be moved around into contact with the opposite edge of the blade in the manner illustrated in dotted lines in Figure 2.

In Figure 5 I have illustrated a modified form of the invention in which the trunnion 16 may be threaded and extended beyond the portion 17 to receive a nut 18 whereby, by tightening the nut the guard may be positively held in place against movement.

In Figure 6 I have illustrated a modified form of my invention in which the blade 10 corresponding to the blade 10 of the first form is formed at one end with a threaded socket 19 in which to receive the threaded member of a handle 20, the latter being furnished with conventional type of safety razor outfit, the handle being used for the safety razor blade holder. In other respects this form of the invention is identical to the 110 form first described.

Thus, it will be seen that I have pro-

vided a novel device which will positively and effectively protect one edge of a double edge blade while the other is being stropped and will also permit the guard or protected device to be almost instantaneously adjusted to guard either one edge or the other as desired. It will also be apparent that the addition of the improvement above set forth involves a negligible expense and 10 that the advantages to be obtained by the use thereof are great and many in comparison to the form of stropping devices heretofore provided.

While I have illustrated and described 15 my invention with some degree of particularity, I realize that in practice various alterations therein may be made. I therefore reserve the right and privilege of changing the form of the details of construction or 20 otherwise altering the arrangement of the correlated parts without departing from the spirit of the invention or the scope of the appended claims.

Having thus described my invention, what 25 I claim as new and desire to secure by United States Letters Patent is:

1. A stropping device including a plate, a pair of studs thereon, a second plate hav-

ing slots to receive the stud and adapted to receive a double edge blade between said 30 plate, the first plate having its ends bevelled, a guard member having parallel ends the inner faces of said ends being grooved to receive the bevelled ends of the first plate whereby the guard may be automatically 35 held in either one position or the other adjacent either edge of the first plate, and means for pivotally mounting said guard for movement in the manner stated.

2. A stropping device including a blade 40 holder, means for supporting a double edged blade thereupon, said holder having the ends thereof bevelled, a resilient guard member having its ends grooved to receive the bevelled ends of said blade holder whereby the 45 guard may be automatically held in either one position or the other adjacent either edge of the blade, and means for pivotally mounting said guard for movement in the manner stated. 50

In testimony whereof I affix my signature in presence of two witnesses.

PATRICK J. DWYER. [L.S.]
